UNITED STATES PATENT OFFICE

HERBERT J. CRABBS, OF WILKINSBURG, PENNSYLVANIA, ASSIGNOR TO WESTINGHOUSE ELECTRIC AND MANUFACTURING COMPANY, A CORPORATION OF PENNSYLVANIA

DISCONNECTING SWITCH

Application filed November 5, 1925. Serial No. 67,021.

My invention relates to electrical apparatus and particularly to disconnecting switches.

One object of my invention is to provide a disconnecting switch that shall be adaptable both for horizontal and vertical mounting.

Another object of my invention is to provide a disconnecting switch that shall be free from moving joints that are at the same time current-conducting joints.

10 A further object of my invention is to provide a disconnecting switch in which the moving contact member shall be connected to a terminal member by a flexible conductor having resilient guiding means for controlling 15 the position of the flexible conductor during movement of the movable contact member.

Yet another object of my invention is to provide an improved housing for the end of the switch blade.

20 In mounting disconnecting switches, it is customary to support the current-carrying elements of the switch on petticoat insulators. Such insulators, when supported in an inverted position, are capable of collecting 25 moisture on the undersides thereof, and such bodies of moisture cause dangers of flash-over between the current-conducting members and ground and between current-conducting members themselves. Such moisture also soaks into and along the insulator pins with the result that the insulators are frequently broken by the expansive and contractive forces incidental to freezing and thawing. Accordingly, it has been found 30 necessary to so design disconnecting switches that any petticoat insulator on the movable contact member shall always be in such a position that as to be self-draining.

Heretofore, it has been customary to limit 40 the application of any particular disconnecting switch to either a horizontal or a vertical mounting. With my improved disconnecting switch, I am able to change the mounting of the switch from the vertical to the horizontal 45 position without inverting any of the petticoat insulators by simply changing the supporting arm that carries the petticoat insulator supporting the movable contact member.

Disconnecting switches are frequently 50 mounted out-of-doors and must be operated

under all sorts of weather conditions such as when the entire apparatus is covered with ice or sleet. It has, therefore, been found advantageous to house the end of the switch blade in such manner that the housing does not carry the major portion of the current. 55

In providing for opening and closing such housing, I take advantage of the fact that ice is weakest in tension and have so designed the housing that there is no opportunity for 60 ice to be under compression or direct shearing stresses during the movements of the housing parts. I am enabled to secure this result by providing a longitudinally split housing that is flexibly mounted and the constituent parts 65 of which are each provided with a cam surface that cooperates with the switch blades in a wedging action during opening and closing movements thereof.

In the accompanying drawings, 70

Figure 1 is a view in elevation of a disconnecting switch embodying my invention, mounted in the vertical position,

Fig. 2 is a similar view showing the switch mounted in a horizontal position, 75

Fig. 3 is an elevational view of the housing for the contact members of the switch,

Fig. 4 is a view, partially in section and partially in elevation, of the housing taken along the section line IV—IV of Fig. 3, and 80

Fig. 5 is a perspective view of one of the housing members.

My invention comprises, in general, a frame 1 that supports a pair of spaced insulators 2 and 3, which, in turn, support a stationary contact member 4 and a terminal member 5, respectively, between which is mounted a shaft 6 that supports and actuates an insulator 7 that serves as a mounting for a movable contact member 8. The stationary contact member 4 terminates in a weather-proof housing 9 of particular construction. 85

The frame 1 may consist of any arrangement of angle or channel irons or a slate base, as desired. In the preferred construction, however, the disconnecting switch is mounted on a channel iron at the factory. The insulators 2, 3 and 7 are preferably of the well known petticoat type, which, when inverted, are capable of collecting moisture 90

on the under surfaces thereof. Accordingly, it is essential that the insulators 2, 3 and 7 shall always be so mounted as to be self-draining in order to avoid danger of flashovers from the electrical-current-carrying points to ground and between each other and deterioration incidental to freezing and thawing.

The insulator 2 supports the stationary contact member 4 that terminates in the housing 9 and an arcing horn 11. The arcing horn 11 is preferably resiliently mounted, as at 12, in order to afford greater flexibility and thereby to permit the contact members 4 and 8 being further removed from each other at the periods of engagement and disengagement of the arcing horns.

The insulator 3 supports the terminal 5 that may be of any preferred type, of which there are a large number on the market, and, in addition thereto, it supports a relatively long and stiff spring 13 that is provided with openings 14.

The material of the spring 13 is such that it may have movement of a relatively large range and, at the same time, support the weight of a flexible conductor 15 threaded through the openings 14 for connecting the moving contact member 8 to the terminal member 5. The spring 13 prevents the loops of conductor 15 from falling across adjacent phases of the switch or switches during movement of the movable contact member 8 and, at the same time, eliminates the necessity for the elaborate knuckle joints and struts, heretofore employed in such disconnecting switches.

The shaft 6 is operated by any suitable mechanism (not shown). A collar 16 is clamped to the shaft 6, one part of which carries lugs 17 that cooperate with suitable springs 18 in the frame 1 for preventing injurious jars during the movement of the switch.

In Fig. 1, the upper part of the collar 16 is shown as comprising an elongated arm 19 that terminates in a seat 21 for the insulator 7. The insulator 7 carries a relatively movable contact member 8 that is in the form of a switch blade for engagement with the stationary contact member 4. The switch shown in Fig. 1, is particularly adapted for vertical mounting as the length and inclination of the arm 19 is such that the insulator 7 is self-draining when the switch is in a closed or solid-line position and when it is in the open or dotted-line position.

In the form of my invention shown in Fig. 2, the upper part 22 of the collar member 16 directly serves as the seat 23 for the insulator 7. This form of my invention is particularly adapted for the horizontal mounting of the switch, since the insulator 7 is in a self-draining position both in its closed or full-line position or in its open or dotted-

line position. The insulator 7 carries also an arcing horn 24 for cooperation with the arcing horn 11. A spring 25 may be inserted at the base of the arcing horn 24 if desired.

Referring particularly to Figures 3 to 5, the housing 9 for the contact members comprises two complementary castings or sheet-metal stampings 30 that may be termed of trough or clam shape. The members 30 engage each other along substantially their entire peripheries, thereby enclosing contact fingers 31 that engage the movable contact member 8 and complete the principal electrical circuit. The purpose of the housing section 30 is primarily that of protection and not that of current carrying. The housing sections 30 are each supported by a flexible strip of metal 32, such as bronze, that is connected by suitable bolts 33 to a base portion 34 of the switch member 4. The contact fingers 31 are independently supported by the base portion 34 by means of bolts 35. The base 34 fits in between the metal strips 32 and substantially closes the back part of the housing 9.

The metal strips 32 further serve to bias the housing elements 30 into firm engagement with each other. The housing members 30 are provided, at their outer ends, with outwardly cam edges 36 that cooperate with the movable contact blade 8 for the purpose of prying or wedging the parts 30 apart during the opening and closing movement of the housing.

The lower edges of the housing 30 are provided with notches 37 for the reception of the switch blade 8 when the switch is in a closed position. The housing 9, therefore, completely encloses and protects the end of the switch of the movable contact blade 8. Since ice and sleet are weakest when under tension, I am enabled to open the housing 9 with a minimum effort for the reason that the only force that such ice can exert is in tension across the line of cleavage defined by the edges of the sections 30. Accordingly, I have provided cam surfaces 38 on the upper portion of the notches 37 that are oppositely disposed so that the blade 8, when moved to open position, will actuate both sections 30 outwardly as the blade passes over the internal cam surfaces.

Assuming the switch to be in the open position, movable contact member 8 is brought between the cam surfaces 36 with a sharp blow, which blow is centered at the edges of the sections 30 that are then split apart. After the blade 8 has entered the notches 37, the housing 9 closes under the influence of the spring blades 32. When it is desired to open the switch, the blade is moved outwardly against the inner surfaces 38 of the notches 37 and the housing elements 30 are again split apart.

The disposition of the insulators 2, 3 and

7 is such that they are subjected to combined compression and bending forces during the circuit-closing movement and combined tension and bending forces during the circuit-opening movement.

5 In the operation from the open to the closing position, the operator causes shaft 6 to rotate in a clockwise direction, whereupon, the arcing horn 24 is brought into engagement with the arcing horn 11, the flexible conductor 15 is extended and the spring 13 is slightly flexed during the turning of the movable contact member 8 into engagement with the housing 9. When the movable contact blade 8 engages the stationary contact member 4, the housing sections 30 are split apart and the blade 8 enters the notches 37 and between the contact fingers 31, whereupon the circuit is completed. If it is desired to open the switch, the shaft 6 is rotated in a counter-clockwise direction, when the foregoing steps take place in reverse order.

It will thus be seen that I have devised 25 a disconnecting switch that may be easily fitted for either horizontal or vertical mounting. I have also eliminated the knuckle joints, braces or the like, by utilizing a flexible connector between the terminal and the 30 movable contact member which is guided by a spring of novel construction.

I have further devised a housing for the 35 end of the switch blade, of such form that the switch blade is completely housed and in which any resistance offered by ice or the like to movement of the housing, must be along the lines of tension in the ice. Since ice is weakest in tension and since the blade members of such disconnecting switches move 40 with considerable force, I am able to break such an ice coating without undue expenditure of energy.

While I have shown but a single embodiment of my invention, further changes and 45 modifications may be made therein without departing from the spirit and scope thereof, and I desire, therefore, that only such limitations shall be placed thereupon as are imposed by the prior art or are specifically set 50 forth in the appended claims.

I claim as my invention:

1. An ice shield for a switch member comprising a pair of complemental trough shaped members, means for supporting the members 55 and biasing them into engagement along their adjacent edges, and means for guiding a blow delivered either externally or internally to the shield for the purpose of separating the constituent members thereof to a plane defined by the engaging edges, whereby any ice or sleet tending to keep the shield closed is broken under tension.

2. A housing for a switch structure split longitudinally and having internal and external cam surfaces on the subdivisions there-

of for cooperation with a switch blade for opening the housing by the lateral displacement of a portion thereof.

3. The combination with a switch blade, of a longitudinally-split ice shield for the end thereof, the ice shield having an internal and an external cam surface for co-operation with the switch blade for opening the ice shield by the lateral displacement of a portion thereof.

4. In combination with a disconnecting switch including a base supporting a terminal and a stationary contact in spaced relation, a shaft disposed intermediate said terminal and said contact, and an insulator for supporting a movable contact in electrical connection with said terminal, detachable clamping means for supporting said insulator on said shaft in one relation to said base when the switch is mounted with its base horizontal, and a second clamping means interchangeable with the first said clamping means for supporting said insulator on said shaft in a different relation to said base when the switch is mounted with its base in vertical position.

5. In combination with a disconnecting switch, elements including a base, a movable contact, a rocking shaft for actuating the contact, and a petticoat insulator for mounting the said contact in fixed relation with said shaft, a pair of interchangeable supporting members, each of which is adapted to cooperate with the shaft to support the said insulator, whereby the petticoat insulator may be retained in a position in which said petticoats are self-draining through the selection of the proper member for its support corresponding to the horizontal or vertical position in which the switch is mounted.

6. In combination with a disconnecting switch comprising a stationary contact member, a movable contact member, an insulator for supporting said movable contact member, and a shaft adapted for rotatably supporting said movable contact member, interchangeable clamps for mounting said movable contact member on said shaft in either of two predetermined relations.

7. In combination with a disconnecting switch comprising a stationary contact member, a movable contact member, an insulator for supporting said movable contact member, and a shaft adapted for rotatably supporting said insulator, interchangeable clamps for mounting said insulator on said shaft in either of two predetermined relations.

In testimony whereof, I have hereunto subscribed my name this 23rd day of October, 1925.

HERBERT J. CRABBS.
